(57) CLAIM

The ornamental design for an air conditioner pressure gauge and charging adapter, substantially as shown and described.

DESCRIPTION

FIG. 1 is a front left perspective view of the air conditioner pressure gauge and charging adapter according to the invention.

FIG. 2 is a front elevation view of the air conditioner pressure gauge and charging adapter according to the invention.

FIG. 3 is a rear elevation view of the air conditioner pressure gauge and charging adapter according to the invention.

FIG. 4 is a right elevation view of the air conditioner pressure gauge and charging adapter according to the invention.

FIG. 5 is a left elevation view of the air conditioner pressure gauge and charging adapter according to the invention.

FIG. 6 is a top elevation view of the air conditioner pressure gauge and charging adapter according to the invention; and, FIG. 7 is a bottom elevation view of the air conditioner pressure gauge and charging adapter according to the invention.

The broken line portions of the drawings, including the distal end of the lever (front), the blade underneath the lever, the gauge (rear), the air conditioner charging clamp (front), and the can attachment portion (bottom) are environmental and do not form part of the claimed design.
